INDIRECTLY HEATED CATHODE

Johannes Christiaan Duran, Jozephus Franciscus Dams, and Gerard Charles Antoine Marie Moubis, Eindhoven, Netherlands, assignors, by mesne assignments, to North American Philips Company, Inc., New York, N. Y., a corporation of Delaware

Application January 30, 1956, Serial No. 562,341

Claims priority, application Netherlands February 9, 1955

3 Claims. (Cl. 313—346)

The invention relates to indirectly heated cathodes for use in electric discharge tubes, and more particularly to cathodes of this kind in which the space between the heater element and the cathode sleeve is filled by sintered insulating material.

Frequently it is desirable that the space available between the heater element and the sleeve of an indirectly heated cathode is entirely filled with insulating material, which will be sintered in position. As examples we may mention cathodes having a high operating temperature or cathodes in which a very high electrical insulation between the heater element and the cathode is required. In addition, it is frequently desirable to avoid relative movements of the heater element and the cathode in view of microphonic disturbances owing to variations in capacity between the said parts.

It has, however, been found that it is very difficult to prevent the formation of cavities in the insulating material or between this material and the cathode sleeve during the process of filling the space and after sintering. Sintering may be required in order to degas the insulating material and to prevent said material from falling out of the cathode sleeve.

The formation of such cavities is undesirable, particularly in view of the heat transfer between the heater and the cathode sleeve.

That is, since the thermal conductivity is reduced by such cavities, and since the cavities will be formed at different points in different cathodes, cathodes having different operating temperatures will result, which non-uniformity is undesirable. Further, the heater may become overheated locally so that the heater filament becomes brittle.

The said disadvantages can be entirely avoided by the use of a method of making the cathode in which the insulating material is introduced into the said space by sedimentation from a suspension.

This method provides the advantage of ensuring a partial separation between the finer and coarser particles of the suspension, particularly if the height of fall, i. e., the distance the particles have to travel, is chosen sufficiently large. The coarser particles become located substantially at the bottom and the finer particles substantially at the top.

When the cathode sleeve is closed at one end, the greater part of the coarser particles become consequently located in the proximity of the closed end while the greater part of the finer particles become located in the proximity of the open end. The coarser particles are only slightly sintered and consequently shrink slightly only, while the finer particles subsequent to sintering exhibit a great mechanical strength and satisfactorily seal the open end. The coarser particles produce a porous mass having some resiliency so that the formation of shrink-cavities is avoided.

A height of fall of from 2 to 3 times the length of the space to be filled has proved advantageous particularly

2

when sedimentation is accelerated by the use of a centrifuge.

In order that the invention may readily be put into practice, one embodiment will now be described in detail with reference to the accompanying drawing, in which—

Fig. 1 shows a holder for the cathode sleeve and the suspension during sedimentation, and

Fig. 2 shows a centrifuge provided with such holders, while

Fig. 3 is a sectional view of a cathode of the invention after sedimentation and sintering.

In Fig. 1, reference numeral 1 denotes the emissive part of the cathode, in the case shown a dispenser cathode of the type described in U. S. Patents 2,543,728, 2,700,118 and 2,700,000, reference numeral 2 the cathode sleeve or support in which the emissive part 1 is secured and supported, and 3 the heater arranged in the cathode sleeve 2. The cathode sleeve 2 has a ridge 4 formed in its periphery. The assembly comprising the cathode 1,

the sleeve 2 and the heater 3 is introduced into a metal holder 5 until the ridge 4 engages with the rim of the holder 5. Said holder 5 has a cavity 9 formed in it which is provided with a tapered part which registers with a second cavity within which the cathode sleeve fits.

The holder 5 is arranged together with the cathode assembly in an aperture 7 of a second holder 6 which may, for example, be made of synthetic resin. The cavity 7 has a recess 8 in its bottom in which the cathode 1 is accommodated. The space 9 is now filled with the suspension of the insulating material to be introduced into the cathode sleeve. Preferably use is made of ground and purified Al_2O_3 , 1 kg. of ground Al_2O_3 being suspended in 1 litre of ethyl alcohol. The size of the particles is preferably from 1 to 15 microns. The height of the space 9 is

at least equal to the length of the cathode sleeve 2. The coarser particles of the suspension settle first and consequently come to rest substantially at the bottom in the proximity of the closed end of the cathode sleeve, the mean size of the particles decreasing in the direction from

bottom to top. When the solid substance is deposited, the liquid is decanted or evaporated and the holder 5 is taken

from the holder 6 and heated until sintering of the insulating material occurs. In the cathode finally produced, which is shown in Fig. 3, the filling of the cathode sleeve

consists substantially of coarser particles 12 (from 10 to 15 microns) while the percentage of finer particles 13 (approximately 1 micron) gradually increases towards the open end.

The sedimentation can be considerably accelerated by the use of a centrifuge, as is shown in Fig. 2. The holder

6 can be suspended from an annular member 11 which is supported from arms 10 of a centrifuge. With a height of fall of from 2 to 3 times the length of the cathode, substantially complete sedimentation is produced after a

period of from 5 to 10 minutes at a speed of 3000 revolutions per minute and with a distance between the cathodes and the axis of approximately 10 to 15 cms., the solid substance filling the cathode envelope to the level

shown by a broken line 14 in Fig. 1.

60 The sintering of the Al_2O_3 is effected by heating for two hours at $1000^{\circ}C$. and subsequently for 15 minutes at $1600^{\circ}C$.

It was found that no cavities are formed either during filling or during sintering. It is necessary that the suspension contains particles of different sizes so that preferably ground insulating material is to be used as the initial material.

Although one embodiment of a cathode has been described, that is to say a so-called dispenser cathode, the invention can also be used with tubular cathodes.

What is claimed is:

1. An indirectly-heated cathode comprising a sleeve member and a heater within said sleeve, and pulverulent

insulating material filling up the space between the sleeve member and heater, said space at one end of the sleeve containing a greater concentration of relatively coarse particles of insulating material, said space at the other end of the sleeve containing a greater concentration of relatively fine particles of insulating material, said insulating material being sintered in position.

2. An indirectly-heated cathode comprising a hollow support member, an electron-emitting member mounted in and closing off one end of said hollow support member, a heater element within said hollow support member, and a sintered mass of pulverulent insulating material filling the space within the hollow support member and surrounding the heater element, the portion of said insulating mass adjacent the electron-emitting member comprising

ing mainly coarser particles, the portion of said insulating mass adjacent the other end of said hollow support member comprising mainly finer particles.

3. An indirectly-heated cathode as set forth in claim 1 wherein the pulverulent insulating material is ground aluminum oxide.
